UNITED STATES PATENT OFFICE.

CHARLES MORRILL, OF NEW YORK, N. Y.

IMPROVEMENT IN BIT-BRACES.

Specification forming part of Letters Patent No. 33,899, dated December 10, 1861.

To all whom it may concern:

Be it known that I, CHARLES MORRILL, of the city, county, and State of New York, have invented a new and useful Improvement for Securing Bits in their Braces and Augers in their Handles; and I do hereby declare that the following is a full, clear, and exact description of the construction and operation of the same, reference being had to the annexed drawings, making a part of this specification, in which—

Figure 1 is a view of the lower end of my improvement. Fig. 2 is a plan view showing a bit in its place. Fig. 3 is an edge view. Fig. 4 is a cut section showing a bit in its place. Fig. 5 is a cut section showing a bit entering.

A is a bit-head, to which is secured cam B by pin C. The cam B is moved into the re-

cess in the shank of the bit by spring D which is securely held by screw E.

Operation: Insert the shank of the bit in the aperture of the head of the brace, thus removing the cam B. Cam B is then brought back to its former position by spring D. The shape of the cam B is such that the bit cannot be removed without turning cam B by pressing upon the lever or projection of the same, as shown in Fig. 5.

What I claim as my invention, and desire to secure by Letters Patent, is—

The bit-brace head A and cam B, in combination with the spring D, as described, for the purposes specified.

CHAS. MORRILL.
